ELECTRON FLOW DEVICE

Zed J. Atlee, Elmhurst, Ill., and Robert French Wilson, Washington, D. C., assignors to General Electric X-Ray Corporation, Chicago, Ill., a corporation of New York

Application December 11, 1941, Serial No. 422,530

9 Claims. (Cl. 250—142)

The present invention relates in general to electronics and has more particular reference to an improved X-ray generator.

An important object of the invention is to provide an electron flow device embodying an electron emission source adapted to produce or emit electrons in an extremely efficient fashion, thereby improving the operating characteristics of the electron flow device.

Another important object is to provide an electron emission source of unusually high efficiency; a further object being more particularly to provide an efficient electron emission source comprising an element adapted to be heated for electron emission at relatively low temperature; a further object being to utilize an emission element comprising thorium for highly efficient electron emission.

Another important object is to provide an electron emission element comprising thorium supported on a suitable mounting, such as a tungsten filament; a further object being to support the thorium as a surface film on the supporting filament.

Another important object is to provide an electron emission element comprising a tungsten filament containing thorium at the surface of the filament; a further object being to carbonize the filament whereby to carry the thorium thereon in a sheath of tungsten carbide on said filament.

Another important object is to provide an electron flow device embodying the improved electron emission element as a cathode, in combination with a co-operating anode, enclosed in a sealed evacuated envelope, and to preserve the thorium by providing means for maintaining the exhausted envelope at a high degree of vacuum of the order of 0.02 micron of mercury or better; a further object, to this end, being to provide gettering means within the envelope and preferably comprising a part of the cathode structure, said gettering means being operable at intervals during the service life of the device to maintain the desired degree of vacuum within the envelope for the preservation of the electron emission element for operation at high efficiency.

Another important object is to utilize a suitable evaporable metallic substance, such as barium, for gettering purposes and to provide means for supporting the gettering substance within the envelope and for heating the substance for the evaporation thereof; a further object being to support the gettering substance on a mounting comprising a wire within the envelope and hav-

ing connections extending outwardly of the envelope whereby to heat the wire by energizing it from an external source of electrical power for the selective and controlled evaporation of the gettering substance.

Another important object is to provide means within the envelope, operable as an ionization gauge, for the determination of vacuum conditions within the envelope during the operating life of the device; a further object being to form the gauge as a plate having a connection extending outwardly of the sealed envelope for attachment in an external measuring circuit and operable as an ionic collector, said plate serving, in conjunction with the external measuring circuit, to measure the degree of ionization and hence vacuum conditions within the envelope; a further object being to form the ionization gauge plate as a part of the cathode structure of the device; a still further object being to utilize the said gauge plate as a housing or enclosure for the gettering means to prevent end products of the gettering operation from settling upon the anode and cathode elements of the device.

Another important object is to provide an X-ray generator comprising an anode and a cooperating cathode enclosed within a sealed evacuated envelope, wherein the cathode comprises a thoriated and preferably carbonized tungsten filament; another object being to provide means forming an ionization gauge within the envelope for the determination of vacuum conditions therein; a further object being to provide gettering means operable within the envelope to maintain a sufficient degree of vacuum within the envelope for the preservation of the thoriated filament in condition for satisfactory operation throughout an extended generator service life; a still further object being to utilize an evaporable gettering substance, in combination with means for controlling the evaporation thereof for gettering purposes within the envelope and to form the ionization gauge as a plate enclosing the gettering substance in order to prevent the same, when vaporized, from depositing upon the anode and cathode of the generator.

These and numerous other important objects, advantages, and inherent functions of the invention will be fully understood from the following description, which, taken in connection with the accompanying drawing, discloses a preferred embodiment of the invention.

Referring to the drawing:

Figure 1 is a sectional view taken longitudinally through an X-ray generator embodying

the invention, the figure including a diagrammatic representation of external electrical connections for the operation of the generator; and

Figure 2 is a sectional view taken substantially along the lines 2—2 in Figure 1.

To illustrate the invention, there is shown on the drawing an electronic device comprising an X-ray generator 11, although the several features of the invention are not necessarily limited to generators but may be utilized to advantage generally in electronic devices embodying means forming an electron emitting source.

The generator 11, as shown on the drawings, may comprise a sealed envelope 13 containing an anode 15 and a co-operating cathode 17. The envelope 13 may be formed of any suitable envelope material and may be arranged in any convenient or preferred form. As shown, the envelope may comprise a tubular glass shell having re-entrant necks 19 at the opposite ends of the shell, the anode 15 and cathode 17 being, respectively, supported on said necks at the opposite ends of the envelope. The necks 19 define openings which are closed by seal members 21 and 23 of generally cup-shaped configuration. These members are preferably formed of conducting material and each has an annular rim which forms a glass-to-metal seal 25 with the inwardly facing end of the neck 19 on which it is mounted to thus seal the end of the envelope.

The member 23, at one end of the envelope, carries the anode 15 which, as shown, may comprise a rotary anode element providing a target 22 and, by suitable bearings, turnably supported on a stem 24 which projects outwardly of the end of the envelope through an opening formed in the seal member 23, the stem 24 being sealed in said opening. The anode may be rotated within the envelope by electric motor means including the stationary stator 26 mounted on and outwardly of the envelope.

The member 21, at the other end of the envelope, carries the cathode 17 which, as shown, preferably comprises a plate-like head 28 formed with a pocket 30 in which is mounted an electron emission filament 32 in position to emit electrons in the direction of the anode, when energized.

The filament comprises a highly efficient electron emission source when electrically excited, and to this end, it comprises a suitable support element for thorium. Preferably, the thorium support comprises a filamentary wire of tungsten carrying the thorium at the surfaces of the support filament.

The electron emission filament 32 may be formed by mixing thorium in quantities of the order of 2% with tungsten, sintering the mixture, and then drawing it through a suitable die to produce a filamentary wire comprising tungsten with the thorium component substantially uniformly distributed in the filament. By operating the filament at high temperature, the thorium is driven to the surface of the filament to form a thorium film on the surfaces of the filament. The heating of the filament to form a thorium film thereon need not be accomplished until the filament has been assembled in the electron flow device and may be accomplished as a part of the process of conditioning the finished device for service. The process of thus conditioning the filament merely comprises the heating of the filament to a temperature of the order of the melting temperature of tungsten.

Thorium functions for electron emission when heated to an electron emission temperature sub-

stantially lower than that of tungsten. Consequently, a thoriated filament of the character herein described is characterized by the ability to emit an effective stream of electrons at a temperature substantially lower than the effective operating temperature of a pure tungsten filament. As a consequence, an electron flow device embodying a thoriated filament, in accordance with the teachings of the present invention, is capable of functioning at a lower temperature and hence at appreciably higher efficiency than is the case with devices containing electron emission elements of the character heretofore known.

In order to aid in holding the thorium on the filament during the service life of the device and to thereby maintain the cathode filament as a highly efficient electron source, it is desirable to carbonize the filament in order to provide a surface coating of carbide, specifically a tungsten carbide layer where the filament comprises tungsten, since thorium has a greater affinity and will be held more securely on the filament by the carbide than by pure tungsten. To this end, the filament is preferably carbonized by heating it to a temperature of the order of 2,000 degrees centigrade in a hydrogen bottle or container in the presence of a carbonizing gas such as acetylene. In this fashion, a sheath of tungsten carbide may be applied to the surfaces of the filament to serve as a foundation for holding the thorium on the filament. The carbonizing process should be limited to the surfaces and should not penetrate completely to the center of the filament in order to avoid extreme brittleness. In performing the carbonizing process, the degree of carbonization may be determined by measuring the electrical resistance of the filament from time to time, the resistance of tungsten carbide being substantially higher than that of pure tungsten, so that a desired degree of carbonization may be readily determined by measuring the resistance of the filament being treated and by terminating carbonization when a predetermined resistance has been reached.

The filament, at its opposed ends, is mounted on, electrically connected to, and supported by conductor stems 27 which extend through openings in the head 28 and are mounted in insulating brackets 34 behind the head. The stems 27 are electrically connected with conductors 36 which extend through openings in the seal means 21. These openings are fitted with grommets 29 in which the conductors 36 are secured by globules of glass which not only support the conductors but also insulate the same from the grommet and hermetically seal the openings around the conductors. The cathode head 28 carries a tubular skirt 47 secured at one end on the head and extending at the other end in position enclosing the glass-to-metal seal 25. The skirt is also secured to the seal means 21 as by screws 37 and thus encloses a space 49 between the seal member 21 and the head 28, which space is in open communication with the interior of the envelope 13 through the annular space defined between the end of the skirt 47 and the glass-to-metal seal 25. Within this space, means is provided for performing a gettering operation in order to insure the maintenance of a high degree of vacuum within the envelope.

It should be understood, of course, that an electron flow device functions by the flow of electrons emitted at the cathode and travelin-

to and impinging upon the anode. When the flow device comprises an X-ray generator, the stream of electrons pass from the cathode and impinge on the anode target, thereby generating X-rays at the anode.

For efficient operation of the device as an X-ray generator, the atmosphere within the envelope 13 is preferably maintained at pressures of the order of 0.02 micron of mercury, and the maintenance of low vacuum conditions is of particular importance where the device embodies a thoriated filament in accordance with the present invention. The operation of an electron flow device results in the ionization of any gas particles within the envelope with which an electron may collide during its travel between cathode and anode. Such a collision results in the production of a positively charged ion which may impinge upon the cathode filament and dislodge therefrom a particle of thorium. In order, therefore, to preserve the thorium in situ during an extended service life, it is necessary to reduce the possibility of ionic impact on the cathode filament and consequent dislodgment of thorium by eliminating, as far as possible, the presence of gaseous matter within the envelope. To this end, means is provided for insuring high vacuum conditions within the envelope throughout the service life of the device. To this end, the envelope is first thoroughly evacuated as a part of the manufacture of the device, evacuation being accomplished after the parts of the device have been assembled and sealed in the envelope. During the evacuation of the envelope, which is preferably accomplished by attaching the same to suitable exhaust means, such as an exhaust pump, the device and all of its operating parts are strongly heated in order to remove all impurities, including such gases as may be occluded in the anode, cathode and envelope walls. After the device has thus been exhausted to the greatest possible extent, the envelope may be sealed off and, as a final operation to remove all remaining impurities, a gettering operation may be performed within the envelope. According to the present invention, gettering is accomplished by vaporizing a suitable gettering material within the envelope, more particularly within the space 49. Barium may be utilized as a gettering material, and by vaporizing the same within the envelope, all remaining impurities may be caused to unite with the barium vapor to form innocuous solid gettering end products which, upon condensation of the gettering material, will become deposited within the envelope 13. By arranging the head 28 and the skirt 47 as a housing enclosing the chamber 49 and performing the gettering operation therein, gettering end products will be deposited upon the internal surfaces of the housing defining the gettering chamber 49 and will thus be prevented from becoming deposited either upon the wall surfaces of the envelope 13 or upon the anode and cathode.

Barium or other suitable gettering material may be supported within the chamber 49 and evaporated therein by any suitable or preferred means. Preferably, however, the gettering material is supported by a carrier wire 51 electrically connected at one end on the seal means 21 and at the other end on a conductor 53, the carrier wire 51 having portions intermediate the anchored ends thereof arranged in loops within the chamber 49. The conductor 53 extends through an opening in the seal means 21 and is 75

sealed, as by means of a globule of glass, in a grommet 59 similar to the grommets 29 and, like them, sealed in the member 21.

The gettering material may be supported in any suitable or preferred fashion upon the carrier wire 51, which preferably is a hollow conductor wire enclosing the gettering material and having weakened wall portions. By passing electrical current through the wire 51, as by connecting a suitable electrical power source 57 between a stud 45, mounted on and electrically connected to the seal means 21, and the conductor 53 outwardly of the envelope, the hollow carrier wire 51 may be heated within the envelope to thereby vaporize the gettering material carried by the wire. The material thus vaporized will be projected outwardly of the wire through its weakened wall portions to perform the gettering operation within the chamber 49, resulting end products being deposited upon the inner walls of the tubular skirt 47 and the head 28.

The gettering circuit between the stud 45 and the conductor 53, in addition to the power source 57, preferably includes a meter 61 for measuring current flow in the gettering circuit, an adjustable control rheostat 63, and a control switch 65 for regulating current flow in the gettering circuit for gettering control through regulation of vaporization of the gettering material in the chamber 49. It will be apparent, of course, that sufficient gettering material may be supplied within the chamber 49 to enable successive gettering operations to be performed within the envelope at intervals during the service life of the device to thereby periodically re-establish desired vacuum conditions within the envelope in the event that the vacuum be impaired during the operating life of the device.

40 The device of the present invention also includes means for testing and measuring vacuum conditions within the envelope from time to time by ionization gauge means, including the head 28 and skirt 47 which, it will be noted, are electrically connected on the stud 45 and otherwise insulated from the cathode filament 32 and the anode 15.

45 The degree of vacuum within the envelope 13 is a function of the number of gaseous particles present within the envelope, and the number of such particles, in turn, is a function of the degree of ionization developed as a result of collision between electrons emitted by the cathode filament with any such gas particles present within 50 the envelope. By measuring the degree of ionization within the envelope resulting from a measurable electron flow between cathode filament and anode, it is possible accurately to determine the presence of gas particles within the envelope and thereby determine the vacuum condition at any time during the service life of the device. This may be accomplished by promoting a known 55 electron flow between cathode filament and anode and then measuring the resulting ionization by collecting resulting positive ions on the head 28 and skirt 47 and quantitatively measuring the ions thus collected. To this end, an ionization gauge circuit comprising a meter 67 and a power source 69 may be connected between either of the conductors 36 and the anode stem 24, preferably under the control of a switch 71 and an adjustable current flow regulating device, such as a rheostat 73. By adjusting the rheostat, a known electron flow, as indicated by the meter 60

67, may be established between the cathode and anode.

By applying a negative bias to the head 28 and skirt 47 with respect to the cathode filament 32, as by means of a power source 75 connected between one of the cathode leads 36 and the stud 45, which is electrically connected with the head 28 and the skirt 47, positive ions, produced within the envelope by electronic collision with gas particles, will be caused to impinge upon the head 28 and skirt 47, the extent of such ionic impingement being accurately measurable upon a meter 77 included with the power source 75 in the biasing circuit between the stud 45 and the cathode filament 32. Whenever the meter 77 shows ionization above a predetermined minimum, it will be known that the desired vacuum condition within the envelope 13 has been impaired and that the device should be reconditioned by the performance of a gettering operation in order to recondition the device for operation under ideal conditions for the preservation of the thoriated cathode filament.

It will be understood, of course, that the circuits shown in dotted lines, namely, the ionization circuit including the meter 67, the ionization measuring circuit including the meter 77, and the gettering circuit including the meter 61, are connected with the device in the manner shown only when it is desired to measure vacuum conditions within the envelope 13 and to recondition the device by the performance of a gettering operation. When the device is in service as an X-ray generator, the cathode leads 36 will be connected by conductors to a suitable source of energizing power 81 and the anode and cathode will be connected with a source of unidirectional power 83.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. An X-ray generator comprising an evacuated envelope at a pressure of the order of 0.02 micron of mercury or lower, and an electron emission element comprising thorium and a sheath of tungsten carbide thereon in said envelope and subject to the low pressure conditions prevailing therein.

2. An electron flow device comprising an evacuated envelope at a pressure of the order of 0.02 micron of mercury or lower, and an electron emission element comprising thorium and a sheath of tungsten carbide thereon in said envelope and subject to the low pressure conditions prevailing therein.

3. An X-ray generator comprising an evacuated envelope at a pressure of the order of 0.02 micron of mercury or lower, and a cathode comprising a support formed with a pocket, and an electron emission element in said pocket comprising thorium and a sheath of tungsten carbide thereon and subject to the low pressure conditions prevailing in said envelope, said cathode and said element being arranged and conformed

to direct the flow of electrons from said cathode.

4. An X-ray generator comprising an evacuated envelope at a pressure of the order of 0.02 micron of mercury or lower, and a cathode comprising a support formed with a pocket, and an electron emission element in said pocket comprising thorium and a sheath of tungsten carbide thereon and subject to the low pressure conditions prevailing in said envelope; said cathode and said element being adapted to aid in focusing the impingement of electrons discharged from said cathode upon a target within said envelope.

5. An X-ray generator comprising an evacuated envelope at a pressure of the order of 0.02 micron of mercury or lower and a cathode comprising a support formed with a pocket and an electron emission element in said pocket, said element comprising carbonized tungsten and thorium diffusible in the carbonized tungsten and being subject to the low pressure conditions prevailing in said envelope, said cathode and said element being adapted to aid in focusing the impingement of electrons from said cathode upon a target within said envelope.

6. An X-ray generator comprising an evacuated envelope at a pressure of the order of 0.02 micron of mercury or lower and a cathode comprising a support formed with a pocket and an electron emission element in said pocket, said element comprising carbonized tungsten having a thorium film thereon and being subject to the low pressure conditions prevailing in said envelope, said cathode and said element being adapted to aid in focusing the impingement of electrons discharged from said cathode upon a target within said envelope.

7. An X-ray generator comprising an evacuated envelope at a pressure of the order of 0.02 micron of mercury or lower and a cathode comprising a support formed with a pocket and an electron emission element in said pocket, said element comprising thoriated tungsten carbide and being subject to the low pressure conditions prevailing in said envelope, said cathode and said element being adapted to aid in focusing the impingement of electrons discharged from said cathode upon a target within said envelope.

8. An X-ray generator comprising an evacuated envelope at a pressure of the order of 0.02 micron of mercury or lower, and a cathode comprising a support formed with a pocket, and an electron emission element in said pocket comprising thorium and subject to the low pressure conditions prevailing in said envelope, in which the electron flow through the generator is controlled by the temperature of said element, said cathode and said element being adapted to aid in focusing the impingement of electrons discharged from said cathode upon a target within said envelope.

9. An X-ray generator comprising an evacuated envelope at a pressure of the order of 0.02 micron of mercury or lower, an anode, and a cathode having a pocket, and an electron emission element comprising thorium mounted in said pocket and subject to the low pressure conditions, prevailing in said envelope, said cathode being adapted to aid in focusing the impingement of electrons upon said anode.
